Patented Jan. 3, 1922.

UNITED STATES PATENT OFFICE.

MAY H. NICHOLS, OF POMONA, CALIFORNIA.

BUILDING BLOCKS FOR SCHOOL PURPOSES.

1,402,438.

Specification of Letters Patent.

Patented Jan. 3, 1922.

Application filed February 23, 1921. Serial No. 447,192.

To all whom it may concern:

Be it known that I, MAY H. NICHOLS, a citizen of the United States of America, and resident of Pomona, in the county of Los Angeles and State of California, have invented certain new and useful Improvements in Building Blocks for School Purposes, of which the following is a specification.

10 This invention relates to building blocks and particularly to blocks intended for the demonstration in schools of the construction of buildings.

15 The invention has for its object the provision of a practical device and method for instructing children especially in the kindergarten and primary school grades the first principle of house building and structural work by means of blocks of substantial 20 strength and weight permitting freedom of use and requiring the employment of muscular activity and skill in order that the minds of the children may be trained by the use of practical and substantial constructive 25 material of simple design which may be readily comprehended by the minds of the young, it being the purpose to instill in the children's minds while at play, the principles of design and execution fundamental 30 in character which will aid in the development of thought and action.

An object of this invention furthermore is to provide novel means whereby fragments or parts of a building may be assembled to form structures of different configurations and proportions, leaving much to the individual ideas of the users, the said fragments being readily assembled and held together frictionally and making it possible 40 for the parts to retain their places until they are intentionally disassociated.

With the foregoing and other objects in view, the invention consists in the details of construction, and in the arrangement and 45 combination of parts to be hereinafter more fully set forth and claimed.

In describing the invention in detail, reference will be had to the accompanying drawings forming part of this application 50 wherein like characters denote corresponding parts in the several views, and in which

Figure 1 illustrates a perspective view of a toy or model building showing the application of the invention in practice;

55 Figure 2 illustrates a perspective view of one of the elements;

Figure 3 illustrates a perspective view of another element; and

Figure 4 illustrates a perspective view of a fragment of one of the rafters.

In these drawings 5 denotes one of a plurality of bars, the dimensions of which are immaterial, although, of course, it would be necessary to have them of such cross sectional area as to provide for the formation 60 of grooves 6 on the opposite sides near each end, these grooves being of proper depth to form shoulders which will prevent the elements from disengaging one another when they are assembled, and preferably, the 70 grooves are of such depth as to permit the interlocking elements to lie in contact with one another as the joints between the elements have been formed or established.

The bars may, as stated, be of different 75 lengths and those for the side of the building will, of course, be longer than those for the ends, but this condition will be understood by those skilled in the art and therefore it would be unnecessary, it is thought, 80 to show those that are intended for use at the ends and those for use at the sides.

The bars shown in Fig. 2 may be termed "full length" or "double-headed" bars and they are intended to form elements which 85 completely inclose the wall on which they are used.

In Fig. 3 I have illustrated a single headed bar 7 and it is to be understood that a plurality of such bars are to be employed 90 and they are used where the ends 8 are to interlock or form joints with the ends of the bar 5 whereas the opposite ends are plain, and the said bars 7 are used in forming window or door openings in the structure being produced. Their application to the structure is well shown where they are superimposed at each side of the door and each side of the window and, of course, these elements may be made of different lengths to 95 form the openings at the side or ends of the structure.

The rafter elements 9 are adapted to extend upwardly toward the center of the structure and have their ends abut as at 10 so that they form a bridge-like support for the roofing boards 11. The ends of the rafters which contact each other as at 10 are beveled and the pitch of the roof is determined by the length of the rafters. As a 110 means for anchoring the rafters each rafter near the outer end is provided with a recess

12 which will fit over a recessed portion of one of the members 5, and as the rafter is on an incline, it is necessary to bevel the under surface of the rafter as at 13 in order that this beveled surface may lie on the upper face of the topmost bar 7. Each of the rafters has a pin 14 which forms an abutment or support for the roofing boards and as the outermost roofing board is held against displacement by the pin, the other roofing boards will successively engage the previously placed roofing boards so that the whole structure may thereby be covered.

These building elements can be made comparatively inexpensive on account of the fact that the interlocking parts are practically duplicated on the shorter or longer bars, and a machine when once set to produce the grooves at the end can be used for the bars of different lengths.

I claim:

1. In a toy or model building, bars having oppositely grooved surfaces near their ends, the grooved portion of one bar being adapted to interlock with the grooved portion of contiguous bars extending at right angles to each other, rafters having beveled inner ends and provided with grooves near their outer ends on their lower sides, the said grooved portions of the rafters being adapted to interlock with the grooved portions of

the bars, pins extending upwardly from the rafters near the outer end forming abutments for roofing boards, and roofing boards extending from the rafters at one end of the structure to the rafters at the opposite end thereof.

2. In a toy building, bars having recesses in their opposite sides near the opposite ends, a series of bars having oppositely disposed grooves at one end and having undisturbed surfaces at the other end, the said grooved portions of the bars being adapted to interlock and extend at right angles to one another to form a structure with openings therein, rafters adapted to be placed at each end of the structure, each of said rafters having a beveled inner end adapted to abut the companion rafter, the said rafter having a groove in its under edge near the outer end and a beveled surface extending from the groove to the end of the rafter, the said outer end of the rafter being adapted to interlock with the uppermost bar and the said beveled surface being adapted to bear on the upper surface of the bar thereunder and extending at right angles thereto, abutments projecting upwardly from each rafter near its outer end, and roof covering elements adapted to be supported by the rafters and to bear against the abutments.

MAY H. NICHOLS.
